Des. 203,473

Patented Jan. 11, 1966

203,473

METER HOUSING

Russell F. Shew and Richard L. Catlin, Silver Spring, and Kyung S. Kim, Takoma Park, Md., assignors, by mesne assignments, to Aero-Med Thermal Instrument Company, Inc., Rockville, Md., a corporation of the District of Columbia

Filed Feb. 5, 1965, Ser. No. 83,695

Term of patent 14 years

(Cl. D52—6)

Fig. 1

Fig. 2

Fig. 3

Fig. 4

Fig. 5

FIG. 1 is a front view in elevation of a meter housing showing our new design.

FIG. 2 is a side view in elevation thereof.

FIG. 3 is a rear view in elevation thereof.

FIG. 4 is a perspective view thereof.

The dominant features of the design reside in the portions shown in solid lines.

We claim:

The ornamental design for a meter housing, as shown and described.
